UNITED STATES PATENT OFFICE.

ALBERT H. SAWTELL, OF PROVIDENCE, RHODE ISLAND.

ELECTRICAL STOPPING DEVICE.

1,372,556.

Specification of Letters Patent. Patented Mar. 22, 1921.

Application filed November 7, 1919. Serial No. 336,290.

To all whom it may concern:

Be it known that I, ALBERT H. SAWTELL, a citizen of the United States, residing at Providence, in the county of Providence and 5 State of Rhode Island, have invented certain new and useful Improvements in Electrical Stopping Devices, of which the following is a specification.

My invention relates to electric stopping 10 devices for a member winding threads or filaments.

The essential objects of my invention are, 15 adaptability for embodiment in a ball governing device for the delivery of threads or filaments from rotary members, such as spindles; to stop delivery instantaneously; and to attain this action by means which lightly contacts with the filaments, whereby my device may be utilized not only for 20 ordinary threads, but for infinitesimal filaments, such as silk, which are too delicate to be capable of supporting the weight and withstanding the abrasion of gravity drop wires. Further objects of my invention will 25 appear from an examination of the drawings and the following description.

My invention consists, therefore, in the 30 means and mechanism for attaining the objects and producing the results above specified and suggested, substantially as herein-after claimed.

In the drawings illustrating the principles of this invention and one mode of applying those principles, and which drawings 35 constitute a part of this specification,

Figure 1 is a front elevation of a ball 40 governor delivery device embodying my invention,

Fig. 2 a central vertical section, partially 45 in side elevation, of the same,

Fig. 3, a diagrammatic view of the electric circuit, and

Fig. 4, a front elevation of a winding 50 mechanism effected by the operation of my device.

Like reference characters indicate like parts throughout the views.

In the construction illustrated 7 is the metallic rail or bar of any usual jack or other 55 frame employed for supporting spindles, cops, and the like together with their respective guides and controllers. Mounted on the rail 7 is a metal block or body 8 integral with a base 10 having a channel 11 to receive the rail, and carrying a clamping

screw 12. The block has a central vertical open cylindrical hole 13 with a semispherical bottom forming a seat 15 for a steel ball 16 loose in the hole. A horizontal passage 17 extends from the seat 15 to the rear face 60 of the body, and a passage 18 in alignment therewith extends from the seat to the front face of the body. In the latter is an eyelet 19. A filament 20 from a spindle extends through the passages and eyelet, and beneath the ball 16 which exerts the proper tension for controlling delivery of the filament to the winding element. Beside the eyelet on the front of the body is a loop guide eye 22 through which the filament 65 passes to the winding element. The lower portion of the body is retracted as at 23 and has a transverse bore 24 fast in which is a sleeve 25 of insulating material which has threaded engagement with a screw 27 70 projecting beyond the faces of the body and having a head 28 upon its forward end. Upon its rear end are clamping nuts 30 and 31 bearing against a flange 32 on the insulating sleeve. In the front face of the 75 body above the passage 18, and, in this instance, slightly to one side of a vertical line passing through the latter, is a screw 34 projecting from the face of the body and having a head 35. A swinging arm 37 of 80 light wire, has at its upper end an integral loop or coil 38 loosely surrounding the screw or pin 34. The wire of the coil is continued in this instance to form an arm 39 disposed at an angle to the arm 18 and 85 90 in this instance terminates in a loop 40. The arm 37 is of sufficient length to contact with the member 27 when swinging in an arc. Normally it is supported by the filament 20 in the position shown in broken lines in 95 Fig. 1, but if the filament should break the arm would swing into engagement with the member 27. While the device is operative in the absence of the arm 39 and loop 40 the device is much more effective by the presence 100 105 as these act as a counterbalance and insures against the arm 37 rebounding when it first strikes the member 27.

The arm 37 makes and breaks an electric circuit which controls the operation of the 110 winding member. The latter may be any convenient rotary member such as a spool, reel, or beam, and such member may be supported, driven, started, or stopped by any preferred structure or mechanism. In the 110

construction illustrated in Fig. 4 the winding member is a reel 42 fast on a shaft 43 journaled in supports 45 upon a base 46. Peripheral teeth 48 on the reel engage a gear 49 fast to a driving shaft 50 also journaled in the supports. The shaft 50 is driven by a motor or belt. In this case a driving wheel 51 on the shaft is adapted to receive a belt for driving purposes. Rigid with pinion 49 is one member 53 of a friction clutch whose cone element 54 is upon a sleeve 55 slidable on the shaft 50. A hand lever 57 is pivoted at its lower end upon a pin 58 in a projecting portion 59 of the base, and engages the sleeve 55 by means of a pin 60 in the latter slidable in a slot 61 in the lever. A spring 63 engages at one end the lever 57, and at its other end a pin 65 in the base, and tends to draw the lever and cone from and out of engagement with the fast members 53 of the clutch and thus stop the rotation of the winding member 42. An upturned finger 67 on the lever 57 engages a downwardly projecting portion 69 of an armature 70 pivoted at its opposite end to a plate or bracket 72 fast to one of the supports. Attached to the bracket is the magnet 74 of the armature which when emerged elevates the member 70 and releases the starting and stopping lever 57. The magnet and armature are in a circuit controlled by the arm 37. It has been found advantageous, but not imperative, to employ two electric circuits rather than one, since a current so strong as to most effectively operate the armature 70, is sometimes so excessive as to overheat the arm 37. To obviate this danger two circuits may be employed. When so employed a second magnet 76 is mounted for instance on the bracket 72 having its armature 77 pivoted as at 78 to the plate, and carrying on said end an arm 79 having contact members 80 adapted to engage contact members 82 in an insulating block 83 on the plate 72, one of which is on a circuit wire 84 extending to a battery 85, and the other on a wire 86 extending to the magnet 74. A wire 87 from the battery 85 to the magnet 74 completes this circuit. The magnet or translator 76 is in circuit comprising a wire 89 extending therewith to a battery 90 on the base, a wire 91 from the battery to the textile frame or bar 7, and a wire 92 extending from the relay and clamped at its opposite end between the nuts 30 and 31 in electrical contact with the member 27. This circuit is completed, when the arm 37 engages the member 27, by the base 10, body 8, and member 34.

It will be observed that the circuit last described which immediately includes the governor is the first to operate, and that the member 76 may be employed as an operating magnet rather than as a relay, if it is

desired to omit the auxiliary circuit first described containing the magnet 74.

No claim is made herein *per se* to the tension device herein disclosed, the same being shown, described and claimed in my co-pending application Serial No. 367,471.

I claim:—

1. In a device of the character described, an electric circuit, a metallic governor body in the circuit, a pivot member in the body constituting one circuit terminal, a stop member in the body constituting the other terminal of the circuit, said body being provided with a thread delivery passage adjacent the terminals, and a metallic arm normally pendent and loosely pivotally mounted on the pivot member resting lightly against the filament and movable by gravity into direct contact with the stop member to close the circuit.

2. In a device of the character described, an electric circuit, a metallic governor body in the circuit, a pivot member in the body constituting one circuit terminal, a stop member in the body and insulated from said body constituting the other terminal of the circuit, said body being provided with a thread delivery passage intermediate said members, and a metallic arm normally pendent and loosely pivotally mounted on the pivot member resting lightly against the filament movable by gravity transversely of the passage into direct engagement with the stop member to close the circuit.

3. In a device of the character described, an electric circuit, a metallic governor body in the circuit provided with a transverse passage for delivery of a thread, a pivot member in the body above the passage constituting one terminal of the circuit, a stop member in the body below the passage constituting the other terminal of the circuit, a guide in the body at one side of the passage adapted to receive the thread, and a metallic balance arm normally pendent and loosely pivotally mounted on the pivot member resting against the filament and supported by the thread intermediate the passage and guide and movable by a release from the thread into direct contact with the stop member to close the circuit.

4. In a device of the character described, an electric circuit, a metallic governor body in the circuit provided with a transverse passage for delivery of a thread, and with a vertical hole terminating in a semispherical seat in an intermediate portion of the passage, a ball in the seat adapted to rest on the thread, a thread guide on the body adjacent the passage, a pivot member in the body above and at one side of the passage, a stop member below the passage, said members constituting the terminals of the circuit, and an arm normally pendent and

loosely mounted on the pivot member adapted to rest lightly against and be supported by the thread and movable when released by the thread to gravitate into direct contact 5 with the stop member to close the circuit.

5. In a device of the character described, an electric circuit, a metallic governor body in the circuit, a pivot member in the body constituting one terminal of the circuit, a

10 stop member in the body constituting the other terminal of the circuit, said body being provided with a thread delivery passage adjacent the terminals, a gravitating metallic arm normally pendent and loosely mounted

15 on the pivot member adapted to directly engage the stop member resting lightly against the filament and released by breaking of such filament and to close the circuit, and a counterweight on the arm.

20 6. An electrically operated stop motion for winding machines comprising an electrical governor body provided with a passage for a thread, a pivot member on the body above the passage constituting one circuit terminal, a stop member in the body

25 below the passage constituting the other circuit terminal, an arm normally pendent and loosely pivotally mounted on the pivot member normally resting lightly against and

30 suspended by the thread and movable when released to gravitate and directly engage the stop member and close the circuit, a rotary winding member for drawing the thread through the passage, a stop lever controlling

35 the winding member, a magnet armature also in circuit, and an armature operated by the magnet detachably engaging the lever and disengageable by the closing of the circuit.

7. An electrically operated stop motion 40 for winding machines comprising a governor body provided with a passage for a thread and constituting a part of an electrical circuit, a pivot member on the body adjacent the passage constituting a circuit terminal,

a stop member on the body adjacent the passage constituting another terminal of the circuit, a counter balanced and normally pendent and loosely pivotally mounted on the pivot member normally resting lightly against and suspended by the thread and 45 adapted to gravitate and directly contact with the stop member to close the circuit when released by the thread, a battery in the circuit, a rotary winding member for drawing the thread through the passage, a stop lever controlling the winding member, a second electrical circuit controlled by the translator, a battery in the second circuit of greater strength than the first battery, a magnet also in the second circuit, and an 50 armature operated by the magnet detachably engaging the lever and actuated by the closing of the circuit.

8. In a device of the character specified, a pivoted member adapted to normally rest 55 lightly against a filament, a stop mechanism, embodying electrical connections including a member against which said pivoted member drops into direct contact when the filament is broken, said loosely pivoted member 60 having a portion extended beyond its pivot to serve as a counterweight and to prevent rebounding of said member when it strikes said electrically connected member.

9. In a device of the character specified, a pivoted member having a coil loosely embracing a support therefor and normally supported by resting lightly upon a filament, a stop mechanism embodying electrical connections including a member against which 70 said pivoted member drops and directly engages when the filament is broken, said coil being provided with an integral extension beyond its pivot and looped to form a counterweight. 75

In testimony whereof I have affixed my signature.

ALBERT H. SAWTELL.
